(Cl. D80—11)

Fig. 1.

Fig. 2.

*FIG. 3.**FIG. 4.*FIGURE 1 is a front elevational view of a floor covering display cabinet, showing our new design, the rear being essentially plain;

FIGURE 2 is a front perspective view taken from the bottom and one side thereof, the wings being removed for convenience of illustration;

FIGURE 3 is a top plan view thereof; and

FIGURE 4 is an elevational view taken from the side shown in FIG. 2, the opposite side being a mirror image of the side shown.

The dominant features of the design reside in the portions shown in full lines.

We claim:

The ornamental design for a floor covering display cabinet, as shown and described.
